CONTAINER CLOSURE DEVICE

Karl Ruetz, Zurich, Switzerland

Application February 19, 1952, Serial No. 272,426

Claims priority, application Switzerland March 2, 1951

8 Claims. (Cl. 222—505)

Especially in storing highly volatile liquids and easily drying pastes such as occur, for example, in the perfume industry and pharmaceutical industry, the aim of the manufacturers of container closure devices is to attain as high a closure tightness as possible.

My present invention relates to improvements in a container closure device, comprising a sliding element adapted to slide in two guiding grooves disposed laterally on the container head and a closing element which carries the packing material.

The high tightness of the closure device disclosed herein is attributable to the following features. On said closing element are provided at least one pressure area both in front and to the rear of the container-orifice central axis, and said element projects forwardly in a manner of a roof thereby depressing the closing element in the closed position of the device on to the orifice ridge at said front pressure area. Furthermore, at least one shoulder or molding is provided on the underside of said sliding element for the purpose of depressing the closing element in the closed position of the device on to the orifice ridge at said rear pressure area. Such closing pressure, being applied to at least two pressure areas, ensures a positive tight fit of the closing element.

When, owing to prolonged storage, the packing material shows signs of fatigue and thus of leakiness, an automatic adjustment of said material would be desirable, since the same has lost part of its initial elasticity. For such purpose, a resilient element could be provided on the closing element, the former in the closed position of the device depressing the latter on to the orifice ridge under a pressure which is additional to that provided at said pressure areas.

When the closing element is made of a resilient material, the said resilient element could be formed as an arm punched from and integral with the closing element.

Further features of my present invention may be taken from the following specific description of one form thereof.

In the drawings:

Fig. 1 shows a vertical section of the closure device in closed position,

Fig. 2 is a top plan view thereof,

Fig. 3 shows a vertical section of the device in open position, and

Fig. 4 is a cross-section on the line IV—IV of Fig. 1.

A sliding element 1, made for example of plastic, has a rooflike projection 1a and two shoulders or moldings 1b disposed in the sliding direction and rounded-off at their forward ends 1e. Between said moldings is formed a groove 1c (Fig. 4) in which is provided a catch or notch 1d. The sliding element 1 is guided in longitudinal rabbets 2 provided on the container head 3. The forward portion of a closing element 4 is in the form of a pocket to receive packing material 5. The closing element 4 is rearwardly extended, and an arm 4a punched therefrom is engaged in the groove 1c of the sliding ele-

2

ment and, abutting against the underside of the sliding element 1, depresses the closing element 4. The arm 4a on its free end has a bend 4b shaped to fit the groove 1d in the sliding element.

5 The closing element 4 is bulged in front at 4c. Such bulge forms a first pressure area D₁ situated in front of the central axis IV—IV of the container orifice 6. A pair of second pressure areas D₂ are situated in the rear portion of the pocket for the packing material 5 to the 10 rear of said axis. In the closed position of the device, the rooflike projection 1a of the sliding element is disposed above the pressure area D₁, and the ends of the moldings 1b of said element are disposed above the pressure areas D₂. The pocket for the packing material 5 is rounded-off in its rear portion 4d.

On the container head 3 are disposed an annular ridge 7 about the orifice 6, a ramp 8 and a ridge 9 which in the open position of the device serves as stop for the closing element 4.

20 When assembling the closure device, the closing element 4 with the aid of an assembling means is depressed on to the ridge 7 of orifice 6. While the assembly pressure is maintained, the sliding element 1 is moved tightly over the closing element 4 so that in the closed position 25 of the device there exists a sealing pressure at the three pressure areas D₁ and D₂.

The closure device described is opened as follows. First the sliding element 1 is pulled rearwardly, whereby the bend 4b of arm 4a is disengaged from catch 1d and the pressure areas D₁ and D₂ are relieved. When the arm 4a at the end of groove 1c abuts against the sliding element 1, the closing element 4 is taken along during further movement. The packing material 5 slides over the exterior cone face of the annular ridge 7 and there-by is raised off the orifice 6. The rear edge of the pocket for the packing material then arrives on the ramp 8 whereby the closing element 4 is raised clear off the annular ridge 7. On account of liquid adhesion there has to be a certain free space a (Fig. 3) between the closing element and the container head 3 in the open position of the closure device. The stop 9 limits the path of the closing and sliding elements in the open position of the device.

40 When closing the device, the moldings 1b push the closing element before them, and the latter descends on the ramp 8. The moldings 1b finally engage the pocket for the packing material 5 and depress the same against the annular ridge 7. The sliding-element portion 1a then overlaps the bulge 4c of the closing element, while the bend 4b arrives in the notch 1d and the rearward portion of the closing element 4 abuts against the rear wall of the sliding element which now is blocked and cannot be pushed forwardly any further.

What I claim as new and desire to secure by Letters Patent is:

55 1. Closure apparatus comprising, in combination, a container having a top portion formed with an opening located about a predetermined axis and through which the contents of the container is adapted to flow; closure means mounted on said top portion of said container for movement between a closed position over said opening and an open position away from said opening, said closure means including a sealing material engaging said top portion of said container about said opening thereof when said closure means is in said closed position thereof, and 60 said closure means having a projection extending away from said container and located on one side of said axis when said closure means is in said closed position thereof; and operating means slidably mounted on said top portion of said container and being operatively connected to said closure means for moving the latter between said closed and open positions thereof, said operating means 65

70 to said closure means for moving the latter between said closed and open positions thereof, said operating means

having an end portion engaging and pressing against said projection of said closure means to press the latter against said container at said one side of said axis of said opening, and said operating means having a pair of spaced additional projections extending toward said container and respectively engaging and pressing against said closure means on the opposite side of said axis from said first mentioned projection to press said closure means against said container at a pair of spaced areas on said opposite side of said axis.

2. Closure apparatus comprising, in combination, a container having a top portion formed with an opening located about a predetermined axis and through which the contents of the container is adapted to flow; closure means mounted on said top portion of said container for movement between a closed position over said opening and an open position away from said opening, said closure means including a sealing material engaging said top portion of said container about said opening thereof when said closure means is in said closed position thereof, and said closure means having a projection extending away from said container and located on one side of said axis when said closure means is in said closed position thereof; and operating means slidably mounted on said top portion of said container and being operatively connected to said closure means for moving the latter between said closed and open positions thereof, said operating means having an end portion engaging and pressing against said projection of said closure means to press the latter against said container at said one side of said axis of said opening, and said operating means having a pair of spaced additional projections extending toward said container and respectively engaging and pressing against said closure means on the opposite side of said axis from said first mentioned projection to press said closure means against said container at a pair of spaced areas on said opposite side of said axis, said pair of additional projections, in the closed position of said closure means, being respectively located on opposite sides of the straight line normal to said axis and passing through the latter and said first mentioned projection. 15 20 25 30 35 40

3. Closure apparatus comprising, in combination, a container having a top portion formed with an opening located about a predetermined axis and through which the contents of the container is adapted to flow; closure means mounted on said top portion of said container for movement between a closed position over said opening and an open position away from said opening, said closure means including a sealing material engaging said top portion of said container about said opening thereof when said closure means is in said closed position thereof, and said closure means having a projection extending away from said container and located on one side of said axis when said closure means is in said closed position thereof, and said closure means having a smoothly curved top surface portion extending toward said container and being located on the opposite side of said axis when said closure means is in said closed position thereof; and operating means slidably mounted on said top portion of said container and being operatively connected to said closure means for moving the latter between said closed and open positions thereof, said operating means having an end portion engaging and pressing against said projection of said closure means to press the latter against said container at said one side of said axis of said opening, and said operating means having a pair of spaced additional projections extending toward said container and respectively engaging and pressing against that part of said top surface portion of said closure means located most distant from said container to press said closure means against said container at a pair of spaced areas on said opposite side of said axis, said pair of additional projections, in the closed position of said closure means, being respectively located on opposite sides of the straight line normal to

said axis and passing through the latter and said first mentioned projection.

4. Closure apparatus comprising, in combination, a container having a top portion formed with an opening located about a predetermined axis and through which the contents of the container is adapted to flow; closure means mounted on said top portion of said container for movement between a closed position over said opening and an open position away from said opening, said closure means including a sealing material engaging said top portion of said container about said opening thereof when said closure means is in said closed position thereof, and said closure means having a projection extending away from said container and located on one side of said axis when said closure means is in said closed position thereof, and said closure means having a smoothly curved top surface portion extending toward said container and being located on the opposite side of said axis when said closure means is in said closed position thereof; and operating means slidably mounted on said top portion of said container and being operatively connected to said closure means for moving the latter between said closed and open positions thereof, said operating means having an end portion engaging and pressing against said projection of said closure means to press the latter against said container at said one side of said axis of said opening, and said operating means having a pair of spaced additional projections extending toward said container and respectively engaging and pressing against that part of said top surface portion of said closure means located most distant from said container to press said closure means against said container at a pair of spaced areas on said opposite side of said axis, said pair of additional projections, in the closed position of said closure means, being respectively located on opposite sides of the straight line normal to said axis and passing through the latter and said first mentioned projection, and each of said pair of additional projections being smoothly curved at the portions thereof engaging said top surface portion of said closure means when the latter is in said closed position thereof.

5. Closure apparatus comprising, in combination, a container having a top portion formed with an opening located about a predetermined axis and through which the contents of the container is adapted to flow; closure means mounted on said top portion of said container for movement between a closed position over said opening and an open position away from said opening, said closure means including a sealing material engaging said top portion of said container about said opening thereof when said closure means is in said closed position thereof, and said closure means having a projection extending away from said container and located on one side of said axis when said closure means is in said closed position thereof, and said closure means having a smoothly curved top surface portion extending toward said container and being located on the opposite side of said axis when said closure means is in said closed position thereof; and operating means slidably mounted on said top portion of said container and being operatively connected to said closure means for moving the latter between said closed and open positions thereof and for movement with respect to said closure means when the latter is located at said closed position thereof, said operating means having an end portion engaging and pressing against said projection of said closure means to press the latter against said container at said one side of said axis of said opening, and said operating means having a pair of spaced additional projections extending toward said container and respectively engaging and pressing against that part of said top surface portion of said closure means, means located most distant from said container to press said closure means against said container at a pair of spaced areas on said opposite side of said axis, said pair of additional projections, in the closed position of said closure

means, being respectively located on opposite sides of the straight line normal to said axis and passing through the latter and said first mentioned projection, and each of said pair of additional projections being smoothly curved at the portions thereof engaging said top surface portion of said closure means when the latter is in said closed position thereof, so that said operating means smoothly engages said top surface portion of said closure means during movement of said operating means with respect to said closure means.

6. In combination with a container having a top portion formed with an opening through which the contents of the container is adapted to flow, closure apparatus comprising, in combination, closure means mounted on the top portion of the container for movement between a closed position over the container opening and an open position away from said opening, said closure means including a sealing material at one side of said closure means engaging the top portion of the container about the opening thereof when the closure means is in its closed position, and said closure means having at an opposite side thereof only three mutually spaced pressure areas distributed about the opening of the container in the closed position of said closure means with two of said areas respectively located on opposite sides of said opening; and operating means slidably mounted on the top portion of the container for movement between inoperative and operative positions and being operatively connected to said closure means for moving the latter from said open to said closed position thereof when said operating means moves from said inoperative to said operative position thereof and vice-versa, said operating means having an engaging means with only three engaging portions respectively movable along three paths intersecting said three pressure areas of said closure means, respectively, when said operating means moves from said inoperative to said operative position thereof and engaging said pressure areas, respectively, when said operating means is in said operative position thereof and said closure means is in said closed position thereof to press said sealing material against said top portion of said container about all parts of said opening.

7. In combination with a container having a top portion formed with an opening located about a predetermined axis and through which the contents of the container is adapted to flow, closure apparatus comprising, in combination, closure means mounted on the top portion of the container for movement between a closed position over the container opening and an open position away from said opening, said closure means including a sealing material at one side of said closure means engaging the top portion of the container about the opening thereof when the closure means is in its closed position, and said closure means having at an opposite side thereof only three mutually spaced pressure areas distributed about the opening of the container in the closed position of said closure means with two of said areas located on one side of said axis and with the third of said areas located on an opposite side of said axis; and operating means slidably mounted on the top portion of the container for movement between inoperative and operative

positions and being operatively connected to said closure means for moving the latter from said open to said closed position thereof when said operating means moves from said inoperative to said operative position thereof and vice-versa, said operating means having an engaging means with only three engaging portions respectively movable along three paths intersecting said three pressure areas of said closure means, respectively, when said operating means moves from said inoperative to said operative position thereof and engaging said pressure areas, respectively, when said operating means is in said operative position thereof and said closure means is in said closed position thereof to press said sealing material against said top portion of said container about all parts of said opening.

8. In combination with a container having a top portion formed with an opening located about a predetermined axis and through which the contents of the container is adapted to flow, closure apparatus comprising, in combination, closure means mounted on the top portion of the container for movement between a closed position over the container opening and an open position away from said opening, said closure means including a sealing material at one side of said closure means engaging the top portion of the container about the opening thereof when the closure means is in its closed position, and said closure means having at an opposite side thereof only three mutually spaced pressure areas distributed about the opening of the container in the closed position of said closure means with two of said areas located on one side of said axis and with the third of said areas located on an opposite side of said axis, said two areas being respectively located on opposite sides of a straight line normal to said axis and passing through said third area; and operating means slidably mounted on the top portion of the container for movement between inoperative and operative positions and being operatively connected to said closure means for moving the latter from said open to said closed position thereof when said operating means moves from said inoperative to said operative position thereof and vice-versa, said operating means having an engaging means with only three engaging portions respectively movable along three paths intersecting said three pressure areas of said closure means, respectively, when said operating means moves from said inoperative to said operative position thereof and engaging said pressure areas, respectively, when said operating means is in said operative position thereof and said closure means is in said closed position thereof to press said sealing material against said top portion of said container about all parts of said opening.
